UNITED STATES PATENT OFFICE

LEO JAMES GOLD, OF LOS ANGELES, CALIFORNIA

DESIGN FOR A FREEZING TRAY

Application filed August 22, 1932. Serial No. 44,660. Term of patent 7 years.

To all whom it may concern:

Be it known that I, Leo JAMES GOLD, a citizen of the United States, residing at Los Angeles, in the county of Los Angeles and State of California, have invented a new, original, and ornamental Design for a Freezing Tray, of which the following is a specification, reference being had to the accompanying drawing, forming part thereof.

The figure is a perspective view of a freezing tray showing my new design.

I claim:

The ornamental design for a freezing tray, substantially as shown.

LEO JAMES GOLD.
